CLAIM

The ornamental design for a food storage container for refrigerator, as shown and described.

DESCRIPTION

FIG. 1 is a perspective view of a food storage container for refrigerator, showing our new design;

(Continued)

FIG. 2 is a front view thereof;
FIG. 3 is a rear view thereof;
FIG. 4 is a side view thereof;
FIG. 5 is a another side view thereof;
FIG. 6 is a top view thereof; and,
FIG. 7 is a bottom view thereof.

1 Claim, 7 Drawing Sheets
